UNITED STATES PATENT OFFICE.

CARL SIEMENS, OF ST. PETERSBURG, RUSSIA.

HYDROCARBON-BURNER.

SPECIFICATION forming part of Letters Patent No. 470,711, dated March 15, 1892.

Application filed December 5, 1890. Serial No. 373,709. (No model.)

To all whom it may concern:

Be it known that I, CARL SIEMENS, a subject of the Emperor of Russia, and a resident of St. Petersburg, Russia, have invented certain new and useful Improvements in Hydrocarbon-Burners, of which the following is a specification.

My invention relates to hydrocarbon burners or injectors, such as are employed for burning mineral oils or the products of mineral oils in metallurgical furnaces.

My invention further relates to that class of burners by which the hydrocarbons or their products are mingled with air or steam prior to their introduction in the form of flame into a metallurgical furnace.

My invention also relates to the combination with such hydrocarbon-burners of a supporting-stand for said burners.

In the accompanying drawings, which illustrate my invention, similar letters of reference indicate like parts.

Figure 1 is an elevation of my improved hydrocarbon-burner. Fig. 2 is a longitudinal vertical section. Fig. 3 is a transverse section on the line $\alpha\alpha$ of Fig. 2. Fig. 4 is an end view of the nozzle. Fig. 5 is an elevation of the supporting-stand for the nozzle, the oil-duct being shown in vertical section.

My improved hydrocarbon burner or injector A consists of a body portion A', made of any suitable material—such as iron, brass, or copper—perforated with two ducts B and C, respectively, for oil and steam or air. The duct B is carried through the cylindrical portion D and through the conical end portion D', which is preferably of refractory material. The cylindrical portion D is tapped at E to receive the screw-thread on the conical part D', and the body portion D is tapped at F to receive the screw-thread G on the cylindrical outer shell H. The shell H fits over the part D, and is provided with the conical end H', of refractory material, which is connected to the shell H in the manner shown in the drawings. The conical portion D' projects slightly beyond the conical portion H'. I have described the part D' and the part H' as connected to the part D and shell H by means of screw-threads. If desired, the part D and the shell H may be made of refractory

material and continued forward to form the parts D' and H'. The shell H is bored in such a manner that a semicircular duct C' is provided between it and the part D and continued in an upward direction through the conical end H' of the burner to form an opening in the shape of a section of a ring, as shown in Figs. 2 and 4.

I is a two-way valve located in the body portion A' and duct C.

J is a duct, which communicates with the duct B and with the duct C when the valve I has its position at ninety degrees from that shown in the drawings, which may be accomplished by means of the handle K, the object of which arrangement is to divert the air or steam normally passing through the duct C' into the ducts J and B, for the purpose of clearing the duct B of any sediment which may have gathered therein.

Referring to Fig. 5, L represents a standard, such as I employ for supporting my improved nozzle when the same is used in connection with a metallurgical furnace.

In practice the standard is placed in such a position as regards the furnace that the end of the nozzle shall be from three to four inches from the port-opening of the furnace.

The standard L is provided with the two supports M, which carry the spindle N. The spindle N is arranged to have a vertical motion and also to turn in the supports M for the purpose of carrying the nozzle or burner A in a horizontally-circular direction from the body of the furnace when not in use. To accomplish these motions, I provide the stuffing boxes O and O' in the supports M.

To effect the vertical movement of the spindle N, I provide the wheel P, upon which is the pinion R, which latter gears with the circular rack S on the spindle.

T represents a pipe communicating with the reservoir containing the liquid fuel, which it is desired to use with the apparatus. T' is a similar pipe communicating with a supply of steam or air. U and U' are valves which respectively control these two pipes.

The spindle N is provided with ducts, as shown at V, the upper of which communicates with the pipe W and the duct B of the burner or nozzle A, and the lower of which communi-

cates with the pipe W' and the ducts C and C' of the nozzle A.

Y and Y' are valves, which respectively control the supply of oil and steam or air to the nozzle.

In carrying my improved invention into effect I may use any of the hydrocarbon oils or their products—such as petroleum, naphtha, or any of the residuums derived from the distillation of petroleum. These oils are delivered to the burner through the pipes T W and duct B. Through the pipes T' W' and ducts C and C', I may supply steam or air. If steam is employed, it should have a pressure of at least seventy (70) pounds to the square inch, but, preferably, should be superheated so as to prevent condensation.

In place of using steam, particularly where high temperatures are desired, I may use compressed air of from eight to ten pounds pressure.

The valves Y and Y' are employed in my device for the purpose of regulating the supply of liquid fuel and steam or air, as desired.

25. In practice I have found the best results from my improved burner when the liquid fuel is of uniform consistency and allowed to flow through the nozzle by its own weight, aided by the injector action of the entering steam or compressed air.

I have described my improved burner as made up of several pieces. This arrangement is simply for convenience of construction, as it will be evident to any mechanic 35 that the device can be made in a single piece.

By the arrangement of ducts in my injector I obtain a solid column of liquid fuel and a fan-shaped body of air or steam under the column of liquid fuel, the result of which is 40 to produce a broad stream of diffused fuel, which burns, when the supply of the two materials is properly regulated, without smoke, and thereby produces the best results obtainable with burners of this description.

45. Having thus described my invention, I claim—

1. A hydrocarbon-burner comprising a body portion having a centrally-located fuel-duct and an independent steam or air duct, the 50 discharge-opening of which is located wholly

under the discharge-opening of the fuel-duct, substantially as described.

2. A hydrocarbon-burner comprising a body portion having a centrally-located fuel-duct and an independent steam or air duct, the 55 discharge-opening of which is located below the discharge-opening of the fuel-duct and in shape is a section of a ring, substantially as described.

3. A hydrocarbon-burner having independent ducts for fuel and steam or air, said steam or air ducts including the fuel-duct, and provided with a discharge-opening located under and behind the discharge-opening of the fuel-duct, substantially as described. 60

4. A hydrocarbon-burner comprising a body portion provided with a conical end and having a centrally-located fuel-duct and an enclosing shell provided with a conical end having a steam or air duct, the discharge-opening of which is located below and behind the discharge-opening of the fuel-duct and in shape is a section of a ring, substantially as 70 described.

5. A hydrocarbon-burner comprising a body 75 portion, a centrally-located fuel-duct, a steam or air duct, the discharge-opening of which has a shape of a section of a ring and is located below the discharge-opening of the fuel-duct, and a duct communicating through said 80 valve with the fuel and the steam or air duct, substantially as described.

6. The combination of a hydrocarbon-burner, a support therefor, comprising a standard, a vertically-adjustable and horizontally-rotatable tubular spindle carried thereby, means consisting of a rack of the spindle for adjusting said spindle, and means consisting of valves for controlling the supply of fuel and steam or air to said burner, arranged as and 90 in the manner set forth.

In witness whereof I have hereunto set my hand and affixed my seal this 3d day of November, 1890.

CARL SIEMENS. [L. S.]
